UNITED STATES PATENT OFFICE.

WILLIAM H. LESTER, OF ELGIN, ILLINOIS, ASSIGNOR TO ILLINOIS WATCH CASE COMPANY, OF ELGIN, ILLINOIS, A CORPORATION OF ILLINOIS.

BUCKLE.

Application filed April 9, 1923. Serial No. 630,781.

To all whom it may concern:

Be it known that I, WILLIAM H. LESTER, a citizen of the United States, residing at Elgin, in the county of Kane and State of Illinois, have invented certain new and useful Improvements in Buckles, of which the following is a specification.

This invention relates to buckles of the kind that are conveniently associated with a belt, strap, web, or similar article, for adjustably connecting the ends thereof. For its principal objects, it aims to combine cheapness in manufacture with simplicity in the formation and assembly of its constituent parts, and with positiveness in the connection which it provides between the belt ends.

An exemplification of this invention is set forth in the accompanying drawing 20 wherein—

Figure 1 is a view in elevation looking toward the rear or inner side of the buckle to which are secured the ends of the associated belt;

Fig. 2 is a plan view of the parts shown in Fig. 1;

Fig. 3 is a detail in longitudinal section taken on line 3—3 of Fig. 1;

Fig. 4 is a similar view showing the parts 30 moved to clamping position;

Fig. 5 is an enlarged end elevation of the buckle; and

Fig. 6 is a perspective view of the clamping elements disassociated from the body 35 of the buckle.

For convenience in explanation, the present buckle is shown, and will be described, in connection with a belt or strap A of conventional design, having one of its ends 10 bent back as at 11 and held upon itself as with the aid of a snap fastener 12. This end of the belt is adapted to be secured non-adjustably to one part of the buckle. The other belt end 13 connects adjustably with 40 the buckle, and is clamped in place by the means which will presently be mentioned.

The present buckle includes a body member B, a clamp C, and an actuating means D therefor. As shown, the body member 50 comprises a front piece 15 in the form of a plate, preferably arched longitudinally, and provided along its opposite sides with

flanges 16 each of which is formed with an inturned lip 17. There is thus formed a channel adapted to receive slidingly the belt 55 end 13.

The body end which lies adjacent the clamp may be advantageously reinforced, and, for this purpose, the material composing the front piece is shown as bent back 60 upon itself at 18 so as to provide in effect, a ridge. Close to this ridge the body member is formed with a pair of upstanding ears 20, between which is extended a pivot pin 21 the ends of which may be upset or 65 enlarged as at 22. This pivot pin also serves as a pivotal mounting for the clamp C and its actuating means D, in the manner that will shortly appear.

The actuating member D is in the general form of a plate having therein an elongated opening 25 capable of receiving the belt end 10 when looped therethrough. By means such as this, the belt end may be conveniently attached to the buckle. Additionally the actuating member is provided with a pair of ears 26 which lie to the inside of the ears 20 which are formed on the body. 70 75

The clamp member C, whose cross section is best shown in Figs. 3 and 4, preferably comprises two angularly related sections 30 and 31 having at their opposite ends ears 32 in which are round holes adapted to register with other similar openings in the other ears previously mentioned. 80 Through all of these ears the pivot pin 21 is extended so as to form a common pivotal connection for all three components of the belt. It is contemplated that the clamp ears 32 will lie just to the inside of the actuator 85 ears 26 as shown, so that the relative transverse positions of the belt components will be substantially constant.

One of the clamp sections, bearing the numeral 31, is preferably curved in the 90 form of a cam, its acting surface being serrated or ribbed as at 33 so as to form a better frictional contact with the belt when pressure is exerted thereupon. An operative connection between the clamp and the 95 actuating means therefor is provided by a lug 35 which projects from the section 30 of the latter, this lug being extended so as to protrude through a slot 36 which is 100

formed in the body of the actuator. This slot is of sufficient width to permit the lug to have a limited play therein, the connection thus provided between these two parts being loose to a certain extent.

In using the present buckle, one end of a belt is secured through the loop of the actuator in the manner indicated in Figs. 1 and 2. The other belt end is slidably fitted 10 within the channel of the body member and adjusted therein to the desired position. During these operations the actuator, together with the clamp associated therewith, is held in a disengaging position such as 15 is shown in Fig. 3. To clamp the sliding belt end to the body of the buckle, the actuating member is swung around the pivot pin 21 as an axis, this movement causing the cam face of the clamp to bear with an 20 increasing pressure upon the belt. Owing to the curvature of the cam section of the clamp, which follows in a general way that of the body member, but with a lesser radius, the clamping pressure upon the belt will be 25 increased according to the extent of movement of the actuator. The loose connection which obtains between this part and the clamp is such as to afford to the former a 30 desirable latitude for play, this being of advantage both preliminary to pressure being exerted by the clamp, and also subsequently when the clamp is firmly engaged with the belt, inasmuch as one belt end is connected to the actuator. The reinforced 35 edge 18 of the body member lies close to the point where the cam exerts its pressure upon the belt, but is slightly offset therefrom, so as to assist not only in resisting the pressure exerted by the cam, but also in 40 providing a ridge over which the belt or strap is required to bend adjacent the point where such pressure is applied. A construction of this kind adds to the security

with which the adjustable belt end may be held by the buckle.

The several compounds of this invention may be variously formed so as to receive any desired ornamentation or other embellishments. In general the construction shown and described is such as may be produced advantageously, both with regard to economy in manufacture, and efficiency in the engagement with the belt. Except as limited by the claims below, I desire that any modifications which utilize the principles of this invention should be included within the scope thereof.

I claim:

In a buckle, the combination of a body member having a plate against which a belt may be slidably rested, there being ears upstanding from opposite sides of the plate, a clamp having a cam face adapted to exert pressure against the belt to thereby force the same tightly against the body plate, the clamp having an ear at each end in proximate relation to the ears on the body member, an actuating means also formed with ears adjacent those on the remaining parts and provided with a loop through which one end of the belt may be secured, there being a hole through each of the several ears and a pin extending through all of the holes to provide a co-axial pivotal connection between the body member, the clamp, and the actuating means, the clamp having a portion of itself extending from its cam face to the actuating means and projected through a slot therethrough in such a manner as to form a loose connection therewith whereby the actuating means may be utilized to operate the clamp, substantially as described.

WILLIAM H. LESTER.
